UNITED STATES PATENT OFFICE.

GEORGE STACKHOUSE, OF BERKELEY, CALIFORNIA, ASSIGNOR TO PACIFIC SPRING BED CO., OF BERKELEY, CALIFORNIA, A CORPORATION OF CALIFORNIA.

FOLDING BED.

1,409,423.

Specification of Letters Patent. Patented Mar. 14, 1922.

Application filed June 4, 1918. Serial No. 238,126.

To all whom it may concern:

Be it known that I, GEORGE STACKHOUSE, citizen of the United States, residing at Berkeley, in the county of Alameda and 5 State of California, have invented certain new and useful Improvements in Folding Beds, of which the following is a specification.

My invention is a folding bed and particularly a folding coil spring bed.

In this specification and the annexed drawing, I disclose my invention in the form which I consider the best, but I do not limit my invention to such form because it may 15 be embodied in other forms and it is to be understood that in and by the claims following the description herein I intend to cover my invention in whatever form it may be embodied.

20 Referring to the drawings:

Figure 1 is a side elevation of my bed unfolded in position for use.

Figure 2 is a plan view of the bed unfolded as in Figure 1.

25 Figure 3 is a view, partly in side elevation and partly in section, of my bed in partly folded condition.

Figure 4 is a view, partly in section and partly in side elevation, of my bed completely folded.

30 Figure 5 is a front view of the bed.

Figure 6 is a detail sectional view of the pivot construction of the foot end of the bed.

In the drawings, 1 indicates a coil spring 35 folding bed and 2 indicates a bed casing in which the bed is mounted as will be more particularly described. The casing 2 is formed only with a rear wall 3 and side walls 4, top and front walls being omitted to 40 permit folding of the bed within and unfolding of the bed outside of the casing. On the inside of the side walls 4 near the forward edge thereof and considerably above the bottom of the casing are secured bearings 45 5 in which are journaled a pivot shaft 6. The bed 1 includes a frame 7 formed of a plurality of pairs of frame members 8, 9, 10, 11 and 12. The frame members 8 are secured at one end to the pivot rod 6 and 50 are pivoted at their other ends by pivots 13 to one end of the frame members 9. The other end of frame members 9 are pivoted by pivots 14 to one end of frame members 10. The other end of frame members 10 55 are pivoted by pivots 15 to one end of frame

members 11. The other end of frame members 11 are pivoted by pivots 16 to one end of frame members 12. The other end of the frame members 12 are pivoted by pivots 17 to the upper part of foot 18. Castors 19 are arranged on the bottom of the foot 18 60 to roll along the floor as the bed is folded and unfolded. The foot 18 is formed of two upright side angle iron members 20 and a panel 21 interposed between and secured to 65 said angle iron members. The lower corners of the foot end of the frame members 12 engage the front flanges 22 of the angle iron members 20 and prevent the foot 18 from swinging inwardly on its pivot 17. 70 The upper corners of the foot end of the members 12 are rounded to permit the foot 18 to swing outwardly a sufficient distance so that it will remain vertical during the folding and unfolding of the bed. A foot 75 board 25 is pivoted by pivots 26 to the upper ends of the foot side angle iron members 20 so that it may swing up into vertical position or down over the bed. The hinged edge of the foot board engages the upper 80 edge of the panel when the foot board is upright whereby the foot board is held in such position.

The frame members 9 to 12 inclusive are formed of angle iron, the horizontal flanges 85 of each member and the members to which it is pivoted engaging each other and preventing sagging of the frame when the bed is unfolded in position for use. Iron bars 27 extend transversely under the bed frame 90 and are secured at their respective ends to the members of each pair of frame members 9 to 12 inclusive, upon which bars are mounted coil bed springs 28. A rectangular frame 30 rests upon and is secured by straps 95 31 to the springs 28 mounted between each pair of frame members 9 to 12 inclusive. The transverse side members of adjacent frames 30 are coupled together by straps 32. The bed may be said to include a plurality of sections, each section comprising a pair of side frame members and its coil springs and mattress supporting means. The bed mattress 35 rests upon the frames 30. A head board 40 is pivotally mounted at the 105 head of the bed by means of hinges 41 pivoted at 42 to the swinging end of frame members 8 and pins 43 are provided on said members for engaging said hinges and holding the head board in an upright position. 110

An angle iron 44 is secured to the lower edge of the head board 40 and extends transversely of the head board. Counterbalancing springs 45 are connected at their respective 5 ends to the ends of angle iron 44 and to brackets 46 secured to the inside of casing walls 4. Rests 50 are secured to the inside of the side walls 4 upon which the bed frame members 10 rest when the bed is 10 folded up, whereby the inner part of the bed is solidly supported in folded position.

The bed is folded into the position shown in Fig. 4, by pushing it into the casing 2 and folding the foot board 25 down upon 15 the mattress, the springs 45 assisting in the initial folding movement of the bed and finally folding the head board upward on the bed. In the folding operation of the bed the members 8 are swung 180 degrees into 20 vertical position downwardly from the shaft 6, the members 9 and 10 are swung into horizontal position rearwardly from members 8 and the head board 40 is swung upwardly against the mattress 35 by the action of 25 springs 45, the members 11 are swung into a vertical position, the members 12 are swung into a horizontal position within the casing 2 and the foot board 18 is brought in front of the casing 2, covering the front of the cas- 30 ing.

The foot board 25 may be upholstered and an upholstered back 60 shown in dotted lines in Fig. 1, may be mounted on the casing 2 to form a davenport when the bed is folded. 35 The bed may be readily unfolded for use simply by pulling it forwardly out of the casing 2, the spring 45 assisting the initial unfolding movement of the bed and unfolding the head board into vertical position 40 until the bed is arrested by the engagement of members 8 in an upright position with lugs 65 and then swinging up the foot board 25. The springs 45 thus serve several purposes, namely, assist the initial folding 45 movement of the bed, fold the head board, assist the initial unfolding movement of the bed and unfold the head board into position for use. The upright position of the members 8 in the unfolded position of the bed 50 makes it possible to fold the bed simply by pushing it inwardly.

The location of the pivot 6 in the forward part and considerably above the bottom of the casing 2, and the length of the bed sections, makes it possible to fold the bed partly 55 below and partly above and mostly to the rear of the pivot in rectangular formation.

The features of construction as above pointed out combine to give the sections of

the bed easy relative swinging leverage and 60 easy folding action to the bed.

Having described my invention, I claim as new and desire to secure by Letters Patent:

1. A folding bed including a plurality of sections pivoted together, a pair of frame 65 members pivotally mounted and pivoted to the rear end section, a head board pivoted to said frame members, and a spring connected to said head board, for assisting the initial folding and unfolding of the bed and for 70 folding and unfolding said head board, said parts being arranged so that said frame members swing into a downwardly extending vertical position, the next two sections into horizontal position rearwardly of said 75 frame members, the head board into horizontal position under said next two sections, the next section upwardly from the rearmost horizontally swung section, and the next sections into horizontal position forwardly of 80 said vertically swung section whereby the bed is folded.

2. A folding bed including a plurality of sections pivoted together, and a pair of frame members pivotally mounted to rest in 85 an upright position when the bed is unfolded, and in a downwardly extending position when the bed is folded, and a head board pivoted to the rear part of the bed, and a spring connected to said head board 90 for assisting the initial folding and unfolding action of the bed and for folding and unfolding said head board.

3. A folding bed comprising four sections and a frame member pivoted together, the 95 frame member being pivotally mounted, the sections being so arranged that when folded the frame member extends downwardly, the next two sections rearwardly, the next section extends upwardly and the next section 100 extends forwardly.

4. A folding bed including a plurality of sections pivoted together, a pair of frame members pivotally mounted and pivoted to the rear end section, a tail board pivoted to the forward end section, said parts being arranged so that said frame members swing into a downwardly extending vertical position, the next two sections into a horizontal position rearwardly of said frame members, the next section into vertical position from the rearmost horizontally swung section, the next sections into horizontal position forwardly of 105 said vertically swung section, and the tail board backwardly upon the forward 110 end section, whereby the bed is folded.

In testimony whereof I affix my signature.

GEORGE STACKHOUSE.
